ATTORNEY

UNITED STATES PATENT OFFICE.

EUGÈNE PROSPER RENAUD, OF PARIS, FRANCE, ASSIGNOR TO BENDIX BRAKE COMPANY, OF CHICAGO, ILLINOIS, A CORPORATION OF ILLINOIS.

BRAKE.

Application filed April 15, 1926, Serial No. 102,134, and in France June 8, 1922.

This invention relates to brakes and is illustrated as embodied in an internal expanding brake for an automobile wheel operated by a servo device engaging the outside of the 5 brake drum.

An object of the invention is to provide simple connections through which the servo shoe applies the brake and also by means of which the servo shoe itself is forced against the 10 brake drum. In one desirable arrangement friction means engageable with the inside of the brake drum, such as a pair of substantially rigid shoes anchored at the bottom of the drum, is arranged to be expanded against the 15 drum by a device operated by an arm extending outside of the brake drum and engaged by the servo shoe, this bringing the servo shoe to the top of the brake drum where it is in a comparatively protected position.

Another feature relates to operating the 20 servo shoe to force it against the outside of the drum by means of interconnected spaced devices such as cams which permit it to have a substantial angular movement with the 25 drum.

The above and other objects and features 30 of the invention, including various novel combinations of parts and desirable particular constructions, will be apparent from the following description of one illustrative embodiment shown in the accompanying drawing, in which:

The figure is a vertical section through the 35 brake just between the open side of the drum and the usual backing plate and showing the brake shoes in side elevation.

The particular brake selected for illustration includes a rotatable brake drum 10 having the usual peripheral cylindrical braking 40 flange, and which in practice is usually closed at its open side by a backing plate or the like which is not shown. Within the drum is arranged the friction means of the brake illustrated as a pair of semi-circular and substantially rigid brake shoes 12 and 14 anchored at the bottom of the drum by being 45 mounted on pivots 16 and 18 projecting from the backing plate towards the head of the drum.

At the upper ends the shoes may be connected 50 by a tension spring 20 serving as a return spring resisting the movement of the shoes against the drum by the brake-expanding means which may be an expanding device such 55 as a double cam 22 mounted on a spindle 24

carried by the backing plate and turned by a lever 26 having a part projecting outside the circumference of the brake drum. For convenience of illustration, shoes 12 and 14 are shown in their "on" position, that is, in engagement with the inner surface of the drum, whereas the cam 22 is shown in its "off" position, in which it is substantially vertical.

The brake is applied by a servo shoe or the like 28 engageable with the outer surface of the 60 brake drum and shown as a substantially rigid arcuate floating shoe. This shoe is notched out as shown to embrace the bend end of the lever 26 so that when the servo shoe moves angularly with the drum it will rock 65 the cam 22 to force shoes 12 and 14 apart against the drum. The servo shoe 28 is forced against the drum in applying the brake, against the resistance of a pair of return springs 30 and 32 connected at its ends, 70 by inter-connected spaced applying devices shown as a pair of cams 34 and 36. These cams have arms 38 shown formed with intermeshing gear or rack teeth so that when the cam 36 is operated the cam 34 is simultaneously operated. The cams 34 and 36 may be 75 mounted on spindles carried by an extension of the backing plate of the brake. The cam 36 is provided with an operating arm or lever 40 which operates both of the cams to apply 80 the brake. When the brake is released, the springs 30 and 32 pull the servo shoe 28 away from the drum as far as permitted by the cams 34 and 38, while the spring 20 serves the 85 double purpose of releasing the shoes 12 and 14 and of acting through the cam 22 and the arm 26 to return the servo shoe 28 to a central initial position.

While one illustrative embodiment has been described in detail, it is not my intention to 90 limit its scope to that particular embodiment or otherwise than by the terms of the appended claims. Most of the subject-matter herein claimed is to be regarded as continued 95 from my application No. 625,072, filed March 14, 1923.

I claim:

1. A brake comprising, in combination, a 100 rotatable drum, friction means engageable with the inside of the drum, an operating device for expanding the friction means against the drum including a part extending outside of the drum, a servo shoe engageable with the outer surface of the drum and operatively engaging the end of said part, means for forc- 110

ing the servo shoe against the outside of the drum, and springs on opposite sides of said means urging the servo shoe away from the drum.

5. A brake comprising, in combination, a rotatable drum, friction means engageable with the inside of the drum, an operating device for expanding the friction means against the drum including a part extending outside of the drum, a substantially rigid servo shoe engageable with the outer surface of the drum and notched to embrace the end of said part, and inter-connected spaced devices acting on spaced parts of the rigid shoe for forcing the servo shoe against the outside of the drum.

6. A brake comprising, in combination, a rotatable drum, friction means engageable with the inside of the drum, an operating device for expanding the friction means against the drum including a part extending outside of the drum, a servo shoe engageable with the outer surface of the drum and notched to embrace the end of said part, and inter-connected spaced cams for forcing the servo shoe against the outside of the drum.

7. A brake comprising, in combination, a rotatable drum, friction means engageable with one side of the drum, a substantially rigid relatively short servo shoe engageable with the other side of the drum and arranged to force the friction means against the drum, and inter-connected spaced devices engaging

spaced portions of said rigid shoe for forcing the servo shoe against the drum.

8. A brake comprising, in combination, a rotatable drum, friction means engageable with one side of the drum, a servo shoe engageable with the other side of the drum and arranged to force the friction means against the drum, and inter-connected spaced cams for forcing the servo shoe against the drum.

9. Brake mechanism comprising, in combination, a brake drum, internal brake shoes supported within the drum to be moved thereagainst, a short inflexible servo shoe outside the drum to be moved thereagainst by cam means and to be rotatably actuated by said drum, operating mechanism connecting the servo shoe with the internal brake shoes to actuate them upon rotatable movement of the servo shoe.

10. A brake comprising, in combination, a rotatable drum, friction means engageable with one side of the drum, a substantially rigid servo shoe engageable with the other side of the drum and arranged to force the friction means against the drum, and inter-connected spaced cams engaging portions of the servo shoe for forcing the same against the drum.

In testimony whereof, I have hereunto signed my name.

EUGÈNE PROSPER RENAUD.
